UNITED STATES PATENT OFFICE.

NESTOR FRIES, FRANK B. EILERS, AND GEORGE U. BRAKE, OF FORT WAYNE, INDIANA,
ASSIGNORS TO TOKHEIM OIL TANK AND PUMP COMPANY, A CORPORATION OF
INDIANA.

GEARING FOR DISPENSING PUMPS.

Application filed April 4, 1921. Serial No. 458,192.

To all whom it may concern:

Be it known that we, NESTOR FRIES, FRANK B. EILERS, and GEORGE U. BRAKE, citizens of the United States of America, and residents of Fort Wayne, in the county of Allen and State of Indiana, have invented certain new and useful Improvements in Gearing for Dispensing Pumps, of which the following is a specification.

10 This invention relates to improvements in gearing for dispensing pumps of the crank operated reciprocating type, and the object thereof is to provide gearing, for actuating the pump, so constructed that by 15 simple manipulations of the crank the pump plunger will be driven accordingly in one direction or the other as desired and through the medium of gearing of different ratios. Thus, during the suction and 20 discharge stroke of the pump, gearing of the low ratio is employed which affords ease of operation, and during the return stroke of the pump which requires comparatively less force, gearing of a higher ratio is employed 25 through which the return stroke is effected with comparatively greater velocity. By this construction the physical energy required to operate the crank during the suction and discharge stroke and return stroke 30 of the pump is approximately uniform, while the return stroke is effected with much greater rapidity than the suction and discharge stroke which requires greater force. A further purpose of the invention 35 is to construct the mechanism for shifting engagement from one gearing to the other so that the operation of shifting may be easily accomplished at any stage during the cycle of movement of the pump by simple 40 manipulation of the crank.

The objects of the improvement are accomplished by the construction illustrated in the accompanying drawings in which:

Fig. 1 is an elevation of the housing 45 which is shown partially broken away to expose the gearing;

Fig. 2 is an end elevation of the apparatus showing portions broken away to expose the working parts;

50 Fig. 3 is a detail view of the adjustable engaging member; and

Fig. 4 is a detail plan view of the stop mechanism showing a horizontal section on the line $\alpha-\alpha$ of Fig. 3.

Similar characters of reference indicate 55 corresponding parts throughout the several views, and referring now to the same:

1 is a pump having a pump-rod 2 by which it is actuated. 3 is a rack-bar fixed on the pump-rod and projecting up through the gear housing 4 and having a series of lugs 5, 6, and 7 that project therefrom respectively in different vertical planes. A movable engaging member 8 mounted upon a longitudinally adjustable shaft 9 in the 65 housing is arranged to be positioned selectively into the paths of the several lugs on the rack, and a series of adjustable stops 10 are arranged to intercept and limit movement of the engaging member in its respective adjusted positions. The purpose of the engaging member and adjustable stops and the lugs on the rack-bar is to interrupt movement of the pump in its discharge stroke at various stages thereof accordingly 70 as the quantity of liquid to be discharged by the pump may be predetermined.

The gear housing 4 is supported upon standards 11 mounted on the pump head 12 and contains the gearing by which the rack-bar is actuated. The gearing is comprised of a pinion 13 fixed on a countershaft 14 and engaged in mesh with the rack-bar.

Also upon the countershaft are fixed an internal gear 15 and intermediate gear 16. A 80 drive-shaft 17 is rotatably mounted in the housing and has also longitudinal movement therein, and upon the drive-shaft are loosely mounted two clutch actuated gears 18 and 19 that have constant meshing engagement with the internal gear and intermediate gear respectively. Between the clutch actuated gears, upon the drive-shaft, is fixed a clutch member that is adapted to 85 selectively engage the clutch gears 18 and 19 accordingly as the drive-shaft is shifted longitudinally in the housing. The gear 18 has at one end thereof a disk 21 that by bearing against the adjacent end of the internal gear prevents disalignment of the 90 clutch gear therewith. Also the intermediate gear 16 has a similar disk 22 at one end thereof that, by bearing against the adjacent end of the clutch gear 19 prevents its disalignment therewith.

The drive-shaft 17 has fixed upon its outer end a crank 23 by which it is rotated and is also shifted longitudinally so as to selec- 100 105

The drive-shaft 17 has fixed upon its outer end a crank 23 by which it is rotated and is also shifted longitudinally so as to selec-

tively engage the clutch 20 with the clutch gears 18 and 19.

- In the operation of the invention, the engaging member 8 is positioned in the path 5 of one or the other of the lugs 5, 6, or 7 on the rack-bar according to the predetermined quantity of liquid to be discharged, and the drive-shaft is shifted longitudinally outward by manipulating the crank so that 10 the clutch engages the clutch-gear 18. The crank is then turned so that the countershaft is rotated through the medium of the clutch gear 18 and internal gear 15 which causes the pinion 13 fixed on the shaft 14 15 to lift the rack-bar until its upward movement is interrupted by the engaging member which intercepts one or the other of the lugs, accordingly as adjusted, and impinges against the corresponding stop, and thus the 20 discharge stroke of the pump which is actuated by the rack-bar is limited.

The drive-shaft is then shifted inwardly so that the clutch is withdrawn from engagement with the clutch gear 18 and operatively connected with the clutch gear 19, 25 whereupon further turning movement of the crank in the same direction as in the former instance causes the countershaft to rotate in the opposite direction through the medium 30 of the clutch gear 19 and intermediate gear 16, thus downward movement is imparted to the rack-bar by the pinion 13. The gear ratio between the clutch gear 19 and the intermediate gear 16 being approximately 35 equal, the downward or return stroke of the rack-bar is effected quicker than the upward or discharge stroke which is effected through the medium of the clutch gear 18 and the internal gear 15 which are of un- 40 equal ratio, and the leverage correspondingly greater. Thus, in making the stroke requiring the greatest force greater leverage is utilized, while the return stroke requiring less force is made comparatively 45 quicker.

By this construction the rack may be driven upwardly with great force and downwardly with great rapidity, and may be reversed in the direction of its stroke at any 50 stage thereof by simple manipulations of the crank.

What we claim is:

1. In mechanism of the class described, a driven member; a gearing for actuating said member; two clutch gears engaged with 55 said gearing; and a cranking device for said clutch gears including a clutch adapted to be shifted selectively into engagement therewith by longitudinal adjustment of the cranking device. 60

2. In mechanism of the class described, a support having bearings therein; a driven member; a countershaft having actuating relation with said member; a drive-shaft including a crank; two clutch gears loosely 65 mounted on said drive-shaft; an intermediate gear fixed on the countershaft and meshing with one of said clutch gears; an internal gear also fixed on the countershaft and meshing with the other clutch gear; 70 and means fixed on the drive-shaft adapted to selectively engage the clutch gears accordingly as the drive-shaft is adjusted longitudinally.

3. In mechanism of the class described, 75 having a driven member; a cranking device including two clutch gears and a clutch for selectively engaging the clutch gears; and a gear mechanism in constant engagement with the driven member and the two clutch 80 gears.

4. In mechanism of the class described, having a driven member; a crank actuated drive-shaft, a gearing engaging the driven member; two clutch gears, each having actuating relation with the gearing and in which said drive-shaft is longitudinally movable; a clutch fixed on the drive-shaft 85 adapted to selectively engage said clutch gears accordingly as the drive-shaft is longitudinally positioned; and means in connection with the gearing and said clutch gears adapted to hold the clutch gears spaced apart. 90

In testimony whereof we affix our signatures, in presence of two witnesses. 95
